IRONING BOARD AND MEANS FOR PIVOTALLY SUPPORTING THE SAME

Alpha Perry Lantz, Washington, D. C.

Application August 25, 1947, Serial No. 770,532

9 Claims. (Cl. 38—129)

1

This application is a companion case to my application filed August 14, 1947, Serial No. 768,514, presenting other embodiments of the invention hereof in improvements in ironing boards and supporting means therefor.

More particularly the invention has for its object the provision of an improved ironing board adapted to be pivotally supported by the opposite wall portions of a cabinet, or the like, whereby to be swung upwardly out of the way when not in use, but to be readily swung downwardly and outwardly into horizontal or ironing position, when desired.

The improved characteristics embrace a novel means for pivoting the end of the board whereby the same will have greatly enlarged convexed seating members fitting complementary concaved supporting members or bearings, to the end that pivot pins or hinges, or details of older devices, are rendered unnecessary and dispensed with, and a strong and efficient structure provided.

More specifically the interfitting convex and concave bearing members referred to comprise members semi-circular in cross-section, one fixed, as in a cabinet, and the other carried by the board for rotative movement therewith, associated with stops for limiting the rotative movement and coincidentally to assist in supporting the board under ironing pressure or strains.

Two embodiments of the invention are illustrated in the accompanying drawings forming part hereof, and the underlying spirit of the invention, together with novel details will be apparent from the descriptions hereinafter contained, when read in connection with the said drawings.

Here, it may be pointed out that a novel basic feature of both embodiments, is the formation of the ironing board, of substantially the same thickness throughout its projecting or ironing portion, with integral lateral extensions of relatively greater depth constituting rocking members, arranged to project into and rotatively engage complementary bearing members on the adjacent walls of the cabinet, eliminating any necessity for separate attachments to be secured to the board with the attending insecurity of fastening means for such attachments, etc., all of which is obviated where, as stated, the board and its immediately associated movable operating parts are integral with and a permanent part of the board itself.

The construction is identical, at the opposite

2

side edges of the board and cabinet, and a reference to the one is to be regarded as applicable to both.

Other features of novelty will be developed in the discussion of the separate embodiments.

In the drawings:

Figure 1 is a vertical sectional view through the ironing board constituting the preferred embodiment of the invention, showing in elevation one 10 of the bearing members on the end wall of the cabinet or other support, it being understood that the board may be of any convenient or preferred length and of a weight to maintain its horizontal operating position as shown, the board being 15 shown with its outer portion broken away;

Figure 2 is a top view of the inner end edge portion of the board in horizontal or ironing position, associated with its bearing in the supporting end wall of the cabinet, the latter being shown in horizontal section;

Figure 3 is a horizontal section on the line 3—3 of Figure 1;

Figure 4 is an edge view of Figure 1 (in the direction of the arrow 4) illustrating the auxiliary stops and braces or supports for the board;

Figure 5 is a vertical sectional view on the line 5—5 of Figure 1.

Figure 6 is a vertical section through the upper or innermost stop;

Figure 7 is an edge view of the plate and stops 30 removed from the cabinet wall;

Figure 8 is a top plan view of the board removed from the cabinet;

Figure 9 is a bottom view of the inner end portion of the same;

Figure 10 is a side edge view of the same; and

Figure 11 is a vertical sectional view, similar to Figure 1, showing the board in vertical position within the cabinet.

Figure 12 is an inner face view showing a modified form of plate with a single supplemental stop.

Figure 13 is a view similar to Figure 1 illustrating the plate of Figure 12 in the second embodiment of my invention, that is, the board formed entirely of metal with the semi-circular wall-engaging projections facing a direction opposite to that illustrated in the preceding series of figures.

Figure 14 is a top plan view of the inner end portion of the board of Figure 13.

Figure 15 is a similar bottom view of the same; and

Figure 16 is a top plan view of the board of Figure 1 projected to ironing position from the cabinet, the latter being shown in transverse horizontal section, and certain details being omitted.

Referring more specifically to the drawings wherein like reference characters refer to the same parts in the respective series of views 17 represents the back wall of a cabinet of any desirable form and size and 18 the side or end walls of the same, on which latter the ironing board 19 is supported to be nested in the cabinet or to be projected outwardly therefrom when in ironing position.

The ironing board 19 is formed entirely of sheet metal shaped to give the same the functional characteristics to be referred to, and side plates 23, screwed as at 21 to the inner faces of the side walls of the cabinet, appropriately spaced to accommodate the desired width of the board, are also formed of sheet metal to have interfitting relationship to the board as will appear.

Such relationship is a rocking or swinging one enabling the board to be positioned vertically in the cabinet or horizontally therefrom as suggested, the structural formations being as follows: The end wall 18 of the cabinet has an opening 22 therein of special contour, as shown, and the plate 20 has an integral outwardly turned flange 23 of the same contour and lining the opening 22 of the end wall for suitable protection and strength in case the end wall is of wood or similar material, and affording a smooth inner working face in said lining of the opening.

This opening in the end plate 20, as also that of the end wall, is of approximately semi-circular shape 24 (Fig. 11) in its lower portion and in its upper portion 25 it is somewhat shaped like a sector, the portion 25 (Fig. 11) being offset outwardly towards the front of the cabinet, as appears in said Figure 1, with the curved or arc-shaped outer wall 26 of the same disposed upwardly or in the opposite direction from the curvature of the semi-circular portion 24 of the opening. This provides a vertical abutment wall 27 and a pair of parallel horizontal abutment walls 28 and 29 to engage and support the board in its two positions.

The board 19 is, as already stated, formed entirely of sheet metal, comprising the flat upper or ironing face 30 and a downwardly bent marginal flange 31, extending substantially therearound save where said flange merges into semi-circular depending plates 32, conforming to the semi-circular open portions 24 and having integral outwardly turned, semi-circular bearings or flanges 33 adapted to bear upon the like curved flanges of the end plates 30 on the end walls of the cabinet, permitting the board to rock upwardly to vertical position or downwardly to horizontal position, as desired.

When the board is in horizontal position a flange 34, projecting outwardly from the bottom of the flange 31, will rest upon the abutment wall 28, connecting the ends of the open portions 24 and 25, and the inner end of the board through the medium of the upper end or terminal 35 of the flange 33, will correspondingly abut the horizontal upper edge or shoulder 29 between said open portions 24 and 25.

The vertical spacing of the stop shoulders 28 and 29 is approximately the distance between the upper surface 30 and bottom of the flange 31, of the ironing board, to engage and support the board when in ironing position at opposite sides of the axis of movement, indicated at 37. When

the board is rocked upwardly it will engage the vertical contact face or edge 27 of the end plate 20, said edge 27 being located in a vertical plane to one side of the axis 37, about the distance of the depth or thickness of the board, as stated, that the board may occupy an approximately true vertical position.

To prevent the board from accidentally swinging out of the cabinet a manually releasable spring latch 36 secured at 38 to and projecting downwardly from the curved wall or flange 26, of the open portion 25, into the path of movement of the flange 34, so that the upper edge of the latter (Figure 11) will slide under and against the V-shaped hump 39, thereby deflecting the spring latch upwardly until passed the said flange, when the latch will spring downwardly again to normal position, in front of the flange 34 and prevent outward rocking movement of the board. When the latter is needed for ironing, the finger of the user may release the latch and free the board as will be obvious.

Struck inwardly from the end plate 26, to secure the added strength or reinforcement of the ironing board therefrom when in use under relatively heavy pressure or strain, are supplemental horizontal stops 40 and 41, the former adapted to contact the innermost upper surface of the board and the latter below the outwardly projecting portion of the board at opposite sides of the axis of movement of the board.

In Figure 8 the board of Figure 1 is shown in top plan view as provided with fine slits or openings 42 therethrough so the ironing portion of the board may be cooled by the passage of air therethrough, but the slits or openings are so narrow that they will not impair the flat ironing surface; the inner portion of the board is formed with a seat or rest 43 for the ironing implement; and hooks 44 (Figure 10) respectively projecting upwardly and downwardly from an intermediate portion of the board, and having connecting shanks 45 passing loosely through the board, afford attaching means for a covering or padding folded over the ironing portion of the board. These features will not be claimed herein because they constitute subject matter of the companion case.

Referring now to the embodiment of the invention illustrated in Figures 12 to 15 inclusive, it will be seen that the same is quite like the embodiment hereinabove set forth, the essential difference residing in the disposition of the semi-circular enlargements or bearing engaging portions on the bottom of the board to engage the bearings in the plate attached to the end walls of the cabinet. In this instance the plates are represented at 46, secured to the end walls 47, as at 48, having the openings 24a and 25a therein (Figure 12) the same as the openings 24 and 25 in the plate 20 of the previously described embodiment, bordered by an inwardly turned flange 49 like the flange 22 (Figure 5) to afford bearing surfaces of corresponding substantial width, the openings 24a and 25a being relatively positioned as heretofore to provide abutment surfaces 50 and 51 arranged in parallel planes, spaced apart vertically, and constituting the connections between the adjacent open portions at their communicating inner ends, the opening between said inner portions being represented at 52. As will be apparent the vertical abutment, corresponding to 27 of the first embodiment, is here represented at 53.

The board of the embodiment now being de-

scribed is represented at 54, the same being formed of sheet metal having a reinforcing surrounding bead 55 constituted by an inwardly folded depending marginal flange 56 of the board.

The bearing engaging portions 57 (integral with and depending downwardly from the board proper) having the semi-circular flange 58, conforming to the curvature 59 of the open portion 24a, are arranged below a broadened portion of the board or lateral extensions 60 thereof, which will project with the rounded extensions 51, into the plates 46 and complementary openings in the end wall 47 of the cabinet so that the extensions 57 may engage and ride upon the curved bottom flange 59 of the open portion 24a, the outer end 61 of this widened portion of the board engaging and riding over the curved upper end 62 of the open portion 25a.

The extended portion 63 of the board connected with said inner end portion 61, will move over the plate 46, and outwardly beyond the portion 61, the board is narrowed somewhat as at 64 to accommodate any covering or padding material that may be passed around the ironing portion of the board, this narrowed portion of the board providing space to accommodate said material while permitting the board to swing into the cabinet and avoid interference from the end wall of the cabinet.

When the board is projected into ironing position the inner end of the board itself will have extended contact with the abutment 51 of the plate, and the projecting or ironing portion may not only have contact of its beaded edge portion 65 with the abutment 50, but may rest upon an additional abutment member 66 struck inwardly from the plate 46.

It will be noted that in both of the herein described embodiments of the invention, the semi-circular bearing engaging members integral with the opposite side edges of the board, and their complementary bearings formed with the supporting plates at the end walls of the cabinet or the like, are of very substantial size or, as illustrated, of a length or diameter approximately equal to about one-half the length of the inner portion of the board which projects into the cabinet so that the supporting bearing for the board is correspondingly extensive and sweeping as distinguished from a mere pivot pin, rod or hinge.

I claim:

1. An ironing board and a support therefor, including a sheet metal plate secured to the end wall of a cabinet or the like, said plate having a bearing portion formed in part by an opening of general sector shape in the upper forward portion of the plate and in part by an opening of approximately semi-circular shape in the lower rearward portion of the plate, said openings communicating with each other and bound by curved and straight walls, the straight walls forming abutments while the curved wall of the semi-circular opening forms a bearing surface, the ironing board being of integral sheet metal formation having a flat ironing surface and a depending semi-circular plate adjacent its inner end and extending longitudinally of said board, the depending semi-circular plate entering the bearing portion and engaging the semi-circular bearing surface, and contact means associated with the ironing board adapted to engage the abutments afforded by the straight walls to limit the swinging movements of the ironing board.

2. An ironing board and a support therefor, including a sheet metal plate secured to the end

wall of a cabinet or the like, said plate having a bearing portion formed in part by an opening of general sector shape in the upper forward portion of the plate and in part by an opening of approximately semi-circular shape in the lower rearward portion of the plate, said openings communicating with each other and bound by curved and straight walls, the straight walls forming abutments while the curved wall of the semi-circular opening forms a bearing surface, the ironing board being of integral sheet metal formation having a flat ironing surface and a depending semi-circular plate adjacent its inner end and extending longitudinally of said board, the depending semi-circular plate entering the bearing portion and engaging the semi-circular bearing surface, and contact means associated with the ironing board adapted to engage the abutments afforded by the straight walls to limit the swinging movements of the ironing board, said

20 bearing portion of the plate having a flange associated with the walls of the sector and semi-circular shaped openings to increase the area of the abutments and the bearing surface, said depending semi-circular plate having a circumferential flange to contact the bearing surface.

3. An ironing board and a support therefor, including a sheet metal plate secured to the end wall of a cabinet or the like, said plate having a bearing portion formed in part by an opening of general sector shape in the upper forward portion of the plate and in part by an opening of approximately semi-circular shape in the lower rearward portion of the plate, said openings communicating with each other and bound by curved and straight walls, the straight walls forming abutments while the curved wall of the semi-circular opening forms a bearing surface, the ironing board being of integral sheet metal formation having a flat ironing surface and a depending semi-circular plate adjacent its inner end and extending longitudinally of said board, the depending semi-circular plate entering the bearing portion and engaging the semi-circular bearing surface, and contact means associated with the ironing board adapted to engage the abutments afforded by the straight walls to limit the swinging movements of the ironing board, said bearing portion of the plate having a flange associated with the walls of the sector and semi-circular

30 shaped openings to increase the area of the abutments and the bearing surface, said depending semi-circular plate having a circumferential flange to contact the bearing surface, the flange of the bearing portion extending away from the ironing board and the circumferential flange of the depending semi-circular plate being similarly extended.

4. An ironing board and a support therefor, including a sheet metal plate secured to the end wall of a cabinet or the like, said plate having a bearing portion formed in part by an opening of general sector shape in the upper forward portion of the plate and in part by an opening of approximately semi-circular shape in the lower rearward portion of the plate, said openings communicating with each other, said sector-shaped opening being bound by a curved wall, a straight horizontal wall and a straight vertical wall, said 50 semi-circular shaped opening being bound by a curved wall and a straight horizontal wall, the straight walls forming abutments while the curved wall of the semi-circular opening forms a bearing surface, the ironing board being of integral sheet metal formation having a flat iron-

ing surface and a depending semi-circular plate adjacent its inner end and extending longitudinally of said board, the depending semi-circular plate entering the bearing portion and engaging the semi-circular bearing surface, and contact means associated with the ironing board adapted to engage the abutments afforded by the straight walls to limit the swinging movements of the ironing board, the straight horizontal wall of the sector-shaped opening joining with the curved wall of the semi-circular opening while the straight horizontal wall of the semi-circular opening joins with the straight vertical wall of the sector-shaped opening.

5. An ironing board and a support therefor, including a sheet metal plate secured to the end wall of a cabinet or the like, said plate having a bearing portion formed in part by an opening of general sector shape in the upper forward portion of the plate and in part by an opening of approximately semi-circular shape in the lower rearward portion of the plate, said openings communicating with each other and bound by curved and straight walls, the straight walls forming abutments while the curved wall of the semi-circular opening forms a bearing surface, said bearing portion of the plate having a flange associated with the walls of the sector and semi-circular shaped openings to increase the area of the abutments and the bearing surface, the ironing board being of integral sheet metal formation having a flat ironing surface, a depending semi-circular plate provided with a circumferential flange entering the bearing portion and engaging the semi-circular bearing surface, and a flange extending laterally from said ironing board and positioned in front of said circumferential flange, said ironing board flange and an upper end portion of the circumferential flange being adapted to engage abutments afforded by the straight walls to retain the ironing board in operative position.

6. An ironing board and a support therefor, including a sheet metal plate secured to the end wall of a cabinet or the like, said plate having a bearing portion formed in part by an opening of general sector shape in the upper forward portion of the plate and in part by an opening of approximately semi-circular shape in the lower rearward portion of the plate, said openings communicating with each other and bound by curved and straight walls, the straight walls forming abutments while the curved wall of the semi-circular opening forms a bearing surface, said bearing portion of the plate having a flange associated with the walls of the sector and semi-circular shaped openings to increase the area of the abutments and the bearing surface, the ironing board being of integral sheet metal formation having a flat ironing surface, a depending semi-circular plate provided with a circumferential flange entering the bearing portion and engaging the semi-circular bearing surface, and a flange extending laterally from said ironing board and positioned in front of the circumferential flange, said ironing board flange and an upper end portion of the circumferential flange being adapted to engage abutments afforded by the straight walls to retain the ironing board in operative position, the flange of the bearing portion being provided with a latch to hold the ironing board in inoperative position.

7. An ironing board and a support therefor, including a sheet metal plate secured to the end wall of a cabinet or the like, said plate having a

bearing portion formed in part by an opening of general sector shape in the upper forward portion of the plate and in part by an opening of approximately semi-circular shape in the lower rearward portion of the plate, said opening communicating with each other and bound by curved and straight walls, the straight walls forming abutments while the curved wall of the semi-circular opening forms a bearing surface, said bearing portion of the plate having a flange associated with the walls of the sector and semi-circular shaped openings to increase the area of the abutments and the bearing surface, the ironing board being of integral sheet metal formation having a flat ironing surface, a depending semi-circular plate provided with a circumferential flange entering the bearing portion and engaging the semi-circular bearing surface, and a flange extending laterally from said ironing board and having connection with one end of the flange of the depending semi-circular plate, said ironing board flange and the other end of the flange of the depending semi-circular plate being adapted to engage abutments afforded by the straight walls to retain the ironing board in operative position.

8. An ironing board and a support therefor, including a sheet metal plate secured to the end wall of a cabinet or the like, said plate having a bearing portion formed in part by an opening of general sector shape in the upper forward portion of the plate and in part by an opening of approximately semi-circular shape in the lower rearward portion of the plate, said openings communicating with each other and bound by curved and straight walls, the straight walls forming abutments while the curved wall of the semi-circular opening forms a bearing surface, said bearing portion of the plate having a flange associated with the walls of the sector and semi-circular shaped openings to increase the area of the abutments and the bearing surface, the ironing board being of integral sheet metal formation having a flat ironing surface and a lateral extension adjacent one end extending longitudinally of the board, said lateral extension entering the bearing portion and having a depending circumferentially-flanged semi-circular plate engaging the bearing surface, the ironing board having contact surfaces adapted to engage the abutments afforded by the straight walls to limit the swinging movement of the ironing board.

9. An ironing board and a support therefor, including a sheet metal plate secured to the end wall of a cabinet or the like, said plate having a bearing portion formed in part by an opening of general sector shape in the upper forward portion of the plate and in part by an opening of approximately semi-circular shape in the lower rearward portion of the plate, said openings communicating with each other and bound by curved and straight walls, the straight walls forming abutments while the curved wall of the semi-circular opening forms a bearing surface, said bearing portion of the plate having a flange associated with the walls of the sector and semi-circular shaped openings to increase the area of the abutments and the bearing surface, the ironing board being of integral sheet metal formation having a flat ironing surface and a lateral extension adjacent one end extending longitudinally of the board, said lateral extension entering the bearing portion and having a depending circumferentially-flanged semi-circular plate engaging the bearing surface, the ironing board having contact

surfaces adapted to engage the abutments afforded by the straight walls to limit the swinging movement of the ironing board, the circumferential flange of the semi-circular plate extending in a direction toward the ironing board.
